UNITED STATES PATENT OFFICE.

CHARLES A. MILLER, OF NEW YORK, N. Y.

VALVE-ROD-ADJUSTING DEVICE.

Application filed April 19, 1919. Serial No. 291,228.

To all whom it may concern:

Be it known that I, CHARLES A. MILLER, a citizen of the United States of America, residing in the borough of Brooklyn, county of 5 Kings, city and State of New York, have invented certain new and useful Improvements in Valve-Rod-Adjusting Devices, of which the following is a specification.

This invention has to do with a valve rod 10 adjusting device, and the principal object is to provide for readily changing the length of an individual valve rod, with reference to the valve rod tappet or other operating device of an internal combustion engine. 15 A further purpose of the improvement is to afford a simple structure that can be produced at a low cost, and permits of making the desired adjustment without removing the valve or any of the engine parts, the 20 simplicity of the device being such that the adjusting operation can be effected in a few moments and without requiring the knowledge or skill of an expert repair man.

Other objects and advantages will be 25 made clear in the following description, and the novel features of the invention will be fully pointed out in the claims at the end of the specification.

In the drawings,—

30 Figure 1 is a sectional view showing the application of a preferred embodiment of the invention to an explosive engine of conventional form.

Fig. 2 is a side elevation of the contact 35 member, forming a part of the adjusting means.

Fig. 3 is a sectional view on the line 3—3 of Fig. 2.

Fig. 4 is a sectional view illustrating the 40 position of the parts during an adjustment, and

Fig. 5 is a detail view showing the relation of the contact member and valve tappet or operating device.

45 In the mechanism here illustrated, which will be understood as showing merely an exemplary embodiment for carrying out the invention, A designates a cylinder-head having a cylinder port controlled by a valve B, which is mounted upon a valve stem C. The 50 valve B is held closed by a spring, in the usual manner, being intermittently opened by an operating device which engages the outer end of the valve stem at regular intervals. Owing to the constant engagement 55 of the operating device and valve stem, the

parts become worn and it is necessary to bring about a relative adjustment in order to obtain the necessary throw of the valve in opening, and it is the particular purpose 60 of this invention to carry out this result by the structure that will now be described.

The outer end of the valve stem, designated by C', is threaded, as at a, to receive a contact member. The latter, designated by D, is 65 hollow for a portion of its length, and threaded interiorly to engage the threaded stem C'. The contact member is preferably formed of hard steel or other metal or material, its closed outer end having a flat surface b, with which the tappet or operating device E engages to open the valve B. To 70 adjust the length of the valve stem and consequently vary the throw of the valve B, it is only necessary to turn the contact member 75 D upon the valve stem in one direction or the other.

It is extremely important that the contact member be held fixedly in its adjusted position, and I accomplish this by providing 80 an elongated opening or slot c in the contact member, and a small opening d in the valve stem. A locking member is provided, preferably in the form of a pin e. The contact member D is turned until the opening c is 85 in alignment with the opening d, and the locking pin e is then inserted through the openings referred to, fitting closely within the small opening d, and preventing any 90 turning of the contact member D. The pin e 90 also serves to hold the retaining plate f in place, the latter engaging the outer end of the controlling spring g, which actuates the valve to its closed position.

When an adjustment is desired, the spring 95 g is pressed sufficiently to release the pin e, which is withdrawn, and the contact member D can then be rotated upon the valve stem to lengthen or shorten the valve stem with reference to the operating device E. 100 This adjusting operation is rendered much more easy by providing for retaining the spring g and plate f in retracted position, and to accomplish this a supplemental small opening h is provided in the valve stem and located inwardly beyond the normal position of the contact member. The opening h 105 is of the same size as the before-described opening d, and its purpose is to receive the pin e after the spring and plate f are forced inwardly to the position of Fig. 4. By inserting the pin in the opening h, the spring 110

and retaining plate are held retracted, as in Fig. 4, and the contact member can then be readily adjusted until the proper relation with the contact member is obtained. Following this, the pin *e* is withdrawn from the opening *h* and again inserted into the opening *d* for holding the parts in normal adjusted position.

While I have described the invention with reference to a more or less specific construction, it is to be understood that I do not limit it to the disclosure of this application, as it susceptible of modifications without departing from the spirit or essential purposes of the improvement, as set forth in the following claims.

What I claim is:

1. The combination with an internal combustion engine, of a valve and valve stem, an operating device for the valve, a contact member having an interiorly threaded portion and an elongated transverse opening, the valve stem also having a transverse opening, a locking pin which passes through the opening in the contact member and fits

closely in the opening in the valve stem, thereby preventing the contact member from turning after it is adjusted, a spring governing the valve, and means adapted to hold the spring out of normal position during adjustment of the contact member.

2. The combination with an internal combustion engine, of a valve and valve stem, an operating device for the valve, a contact member having an interiorly threaded portion and an elongated transverse opening, the valve stem also having a transverse opening, a locking pin which passes through the opening in the contact member and fits closely in the opening in the valve stem, thereby preventing the contact member from turning after it is adjusted, and a spring governing the valve, the stem having a second opening to receive said pin and hold the spring out of normal position during adjustment of the contact member.

In witness whereof, I have hereunto signed my name.

CHARLES A. MILLER.
